US0D1114097S

(12) **United States Design Patent** (10) **Patent No.:** **US D1,114,097 S**
(45) **Date of Patent:** **** Feb. 17, 2026**

(54) **GRIP STRENGTHENER**

(71) Applicant: **Anruiya (Shenzhen) E-commerce Co., Ltd.**, Guangdong (CN)

(72) Inventor: **Zecheng Yu**, Zhejiang (CN)

(73) Assignee: **Anruiya (Shenzhen) E-commerce Co., Ltd.**, Guangdong (CN)

(**) Term: **15 Years**

(21) Appl. No.: **29/983,100**

(22) Filed: **Jan. 9, 2025**

(51) LOC (15) Cl. **21-02**

(52) U.S. Cl.

USPC **D21/684**

(58) **Field of Classification Search**

USPC ..... D21/692, 681, 684, 694, 662, 675, 677, D21/679, 680; D24/215, 211; D23/366 CPC A63B 23/02; A63B 21/22; A63B 23/16; A63B 21/00; A63B 43/00; A63B 23/14

(57) **CLAIM**

The ornamental design for a grip strengthener as shown and described.

DESCRIPTION

FIG. 1 is a front, right and top perspective view of a grip strengthener, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the grip strengthener that form no part of the claimed design.

1 Claim, 8 Drawing Sheets
